ABSTRACT

A golf game in which a plurality of fairways are provided on playing cards or boards preferably simulating an actual golf course, i.e., there could be nine boards with a fairway on each side of the board simulating the eighteen fairways of an actual golf course. Each fairway is marked with distance lines and upon teeing off the player throws a chance number, such as with three dice, which together with a conversion table, indicates how far the player has driven the ball. At that time another chance indicia such as a spinner card is provided corresponding to each fairway, indicating where on the fairway the ball landed, such as in the rough, sand-traps, watertraps, etc. Other chance indicia are provided for each hole for fairway shots, green shots, etc., along with special dice for indicating the number of putts required after the green is reached.

GOLF GAME BOARD APPARATUS

PRIOR ART

The following patent was discovered in a preliminary patentability search, H. H. Ristow, U.S. Pat. No. filed Nov. 12, 1929.

BRIEF DESCRIPTION OF THE INVENTION

The present invention relates to a golf game and more particularly to a golf game in which specific fairways have a plurality of chance controlled devices for indicating advancement of the ball toward the hole.

According to the invention, a golf game is provided in which a plurality of fairways on a playing board can simulate actual fairways on actual golf courses. In its preferred form, there would be 18 playing board fairways which could be implemented with nine cards, for example, with a fairway on each side. Fairways, of course, vary in their given pars and each has a plurality of chance controlled devices for indicating the length of the drive or putt and the character of the drive as, for example, whether the drive will land on the fairway or in a sandtrap, etc. Hence, a very realistic game is provided simulating actual playing conditions on a given golf course.

An object of the present invention is the provision of an improved golf game.

Another object of the invention is the provision of a golf game which simulates actual playing conditions.

A further object of the invention is the provision of a golf game in which an existing golf course can be simulated.

Yet another object of the invention is the provision of separate chance controlled devices for simulating the actual geography of each fairway.

Other objects and many of the attendant advantages of the present invention will be readily appreciated as the same become better understood by reference to the following detailed description when considered in connection with the accompanying drawings in which like reference numerals designate like parts throughout the Figures thereof and wherein:

FIG. 1 is a top view of a typical par 5 fairway playing board;

FIG. 2 is a tee card corresponding to the fairway of FIG. 1;

FIG. 3 is a top view of a fairway card associated with the fairway of FIG. 1;

FIG. 4 is a top view of a green card associated with the fairway of FIG. 1;

FIG. 5 illustrates conventional dice utilized with the present invention;

FIGS. 6, 7 and 8 illustrate special dice associated with green shots of the present invention;

FIG. 9 illustrates a long/short fairway card associated with all of the fairways of the present invention;

FIG. 10 illustrates a "chip and pitch" card utilized with all of the fairways of the present invention;

FIG. 11 illustrates a putt card associated with all of the fairways of the present invention;

FIG. 12 illustrates a par 4 fairway card for utilization in the present invention;

FIG. 13 illustrates a tee card for utilization with the fairway of FIG. 12;

FIG. 14 illustrates a green card for utilization with the fairway of FIG. 12; and

FIG. 15 illustrates a spinner board for utilization with the cards of FIGS. 2, 3, 4, 9, 10, 11, 13 and 14.

DETAILED DESCRIPTION OF THE DRAWING

Referring to FIG. 1, a fairway board is shown generally at 21 having a fairway impressed thereon generally shown at 22 with a tee 23 and green 24 with a hole 26 thereon. A plurality of markers 27 are shown in various stages of play, two of which are disposed on a yard scale which would be typical of a 551-yard fairway. A plurality of sand traps 28 are disposed on fairway 22 together with water trap 29, hedge 31, and trees 32. The wavy line outlining the fairway indicates the rough area 33.

Referring to FIG. 2, a tee card 34 is shown with various indicia such as sand, unplayable lie, rough and water areas thereon, with the in-between areas on the fairway.

Referring to FIG. 3, a fairway card 36 is shown having the indicia sand, unplayable lie, sand and rough with the in-between areas indicating the fairway.

Referring to FIG. 4, green card 37 is shown having the indicia water, sand, twenty yards left, sand, ten yards right, sand and holed-out, with in-between areas indicating the green.

Referring to FIG. 5, typical dice are shown at 38.

Referring to FIG. 6, a folded out die is shown at 39 having numerical indicia of 1 or 2 on each face.

Referring to FIG. 7, an unfolded die 41 is shown having numerical indicia 1, 2 or 3 on each face thereof.

Referring to FIG. 8, a folded out die 42 is shown having numerical indicia 1, 2 or 3 on each face thereof.

Referring to FIG. 9, a long/short card is shown at 43 having unplayable lie areas and fairway areas thereon.

Referring to FIG. 10, a chip and pitch card is shown having various numerical indicia around the periphery thereof, together with a holed-out area.

Referring to FIG. 11, a putt card is shown at 46 having various numerical indicia around the periphery thereof and including a holed-out portion.

Referring to FIG. 12, a fairway playing board 47 is shown having a fairway 48 impressed thereon which includes a tee area 49 and green area 51. The green area 51 has a hole 52 thereon. Various sand traps 53 are indicated on the fairway together with a hedge 54 and a plurality of trees 56. Typical player markers 27 are shown on board 47.

Referring to FIG. 13, a tee card is shown having one sand area illustrated; an unplayable lie area, an out-of-bounds area, and a rough area, which are surrounded by green areas corresponding to the fairway of board 47.

Referring to FIG. 14, green card 58 is illustrated having four sand areas; a ten-yard left area, a fifteen-yard right area, and a holed-out area. This card corresponds to the green of fairway 48.

Referring to FIG. 15, a spinner board is shown generally at 59 having a tee and fairway spinner 61, a green spinner 62, a long-short spinner 63, a chip and pitch spinner 64, and a putt spinner 66. The individual spinners and cards of FIGS. 2, 3, 4, 9, 10, 11, 13 and 14 are constructed so that the cards are inserted from the top through an opening indicated by the dotted lines above the spinners.

OPERATION

To begin play, each player selects a different colored

marker 27 (FIGS. 1 and 12) and begins play at the first tee, such as 23 of FIG. 1, in any numerical order. The order of play on subsequent holes could be determined by the result of the previous hole or holes, such as having the highest scorer of a previous hole going first and the lowest scorer on the previous hole going last.

TEE SHOTS

For tee shots on par 4 or par 5, the player will throw three standard dice (FIG. 5) and add up the total number shown on the dice. The player then consults the yardage chart illustrated below to determine the distance the shot has traveled. Immediately thereafter he spins the tee shot spinner, such as 34 of FIG. 2, which corresponds to the particular fairway he is on to find out the quality of his shot. He then advances his marker to that location on the playing board. A distance scale is supplied with each hole. Each of the players proceed in the manner outlined above until they have all taken a tee shot.

5

landed on the green by spinning green spinner 62. A green may be 120 feet from front to rear and a player may put his ball on the rear section of the green. After he spins putt spinner 66, he may find he is only 3 feet from the pin, or 100 feet. He must then throw the die which corresponds to that length of putt.

CHIPPING AND PITCHING

All shots within 30 yards of a green are designated as a chip or pitch shot and the chip and pitch spinner 64 is used. The area on card 44 in which the spinner stops tells the player how far he must putt for his next shot. He then throws 2 putting die accordingly.

SHOTS WITHIN ONE HUNDRED YARDS

A player whose shot is 100 yards or less to within 30 yards of the green has two options from which to choose. He may throw the dice and use each increment as 5 yards (a 5 would equal 25 yards), or he may elect to throw only one die and use the yardage chart used for all other shots.

LONG OR SHORT SHOTS

If a player throws the dice and the numbers thrown show that his shot was long (i.e., over the green), or short of the green, he must then spin the long/short spinner 63 to determine where his shot landed. Each green is marked on the board showing its length; therefore there are many different numbers a player may throw and still remain on the green.

HAZARDS AND PENALTIES

OUT OF BOUNDS

Designated by O.B. (FIG. 13), add a penalty shot and hit again from the same spot as before.

WATER

Add a penalty shot and play your next shot from the same point as the shot that went into the water from a point behind the water, keeping the location where the ball dropped into the water between the marker and the green.

SAND TRAPS

(Fairway and greens) The player must roll two dice 40 and to get out of the sand safely he must roll above a 4. If he does not he has then left his ball in the sand. If he is successful in throwing above a 4, he then rolls again to see how far his shot has traveled. Note: If a player is in the sand around the green and successfully 45 rolls above a 4, then he spins the chip and pitch spinner 64 to see how far from the pin his ball has stopped.

ROUGH

If a player's ball is in the rough, throw the dice as usual but subtract ten yards from the total because of 50 the rough.

UNPLAYABLE LIE

An unplayable lie is one in which the player cannot

successfully hit his ball. Add one penalty stroke and play the next shot when it is the player's next turn.

It should be understood, of course, that the foregoing disclosure relates to only a preferred embodiment of 5 the invention, and that it is intended to cover all changes and modifications of the example of the invention herein chosen, for the purposes of the disclosure, which do not constitute departures from the spirit and scope of the invention.

10 The invention claimed is:

1. A golf game apparatus comprising:
a plurality of cards, each of said plurality of cards having at least one simulated golf fairway on at least one surface thereof;

15 each of said at least one fairway having a simulated green area therein and a tee;
a plurality of marks spaced along each of said fairways for designating simulated distances from the tee;
a first chance control device for determining the length 20 of a drive from a tee;

a second chance control device for determining the character of said drive; and

25 a third chance control device for determining the number of putts on a green, said third chance control device consisting of a spinner card indicating distance on the green from the hole and a plurality of dice, each of said plurality of dice having a unique number combination.

30 2. The golf game apparatus of claim 1 wherein:
said second chance control device consists of a spinner and one of a plurality of spinner cards, each of said one of a plurality of spinner cards being associated with a separate one of said simulated golf fairways.

3. A golf game apparatus comprising:
a plurality of cards, each of said plurality of cards having at least one simulated golf fairway on at least one surface thereof;

35 each of said at least one fairway having a simulated green area therein and a tee;
a plurality of marks spaced along each of said fairways for designating simulated distances from the tee;

a first chance control device for determining the length of a drive from a tee;

40 a second chance control device for determining the character of said drive, said second chance control device consisting of a spinner and a plurality of different selectively usable spinner cards, each of said spinner cards being associated with a separate one of said simulated golf fairways; and

45 a third chance control device for determining the number of putts on a green.
